TOY

Carlisle Martin, Pershing, Okla.

Application November 5, 1935, Serial No. 48,421

1 Claim. (Cl. 46—51)

The present invention relates to toys and will readily be understood from the following description of a preferred embodiment thereof, taken in conjunction with the accompanying drawings, in which:—

Figure 1 is a plan view of the toy embodying the features of my invention.

Figure 2 is an enlarged detail section taken substantially on the line 2—2 of Figure 1.

Figure 3 is an end view of the handle.

Figure 4 is a detail sectional view taken substantially on the line 4—4 of Figure 1.

Figure 5 is a detail sectional view taken through the two stop loops substantially on the line 5—5 of Figure 4 and showing the flexible ring in elevation.

Figure 6 is a perspective view of the handle per se.

Figure 7 is a detail sectional view taken substantially on the line 7—7 of Figure 1.

Figure 8 is a perspective view of one of the sleeves in the end of the handle.

Figure 9 is a perspective view of the other one of the sleeves.

Figure 10 is a perspective view of the block with the rod projecting therefrom.

Referring to the drawings in detail it will be seen that the numeral 5 denotes a ring constructed of rope or other suitable flexible material. A pair of circular stops 6 are fixed by pins 7 in spaced relation to each other on the ring 5. Numeral 8 denotes a rope or other flexible member having a loop 9 at one end circumjacent the ring 5 between the stops 6. Numeral 10 denotes a block with a rod projecting therefrom denoted by the numeral 11. The other end

of the rope 8 is fixed in the block as indicated at 12. Numeral 14 denotes a hollow handle in each end of which is fixed a sleeve 15 having a flange 16 fixed to the hollow handle. The rod 11 extends through the sleeves so that the handle is rotatable about the rod. On the upper end of the rod there is a nut or equivalent element 17 for the purpose of holding the parts assembled.

In use this device is used by whirling the same 10 in a similar manner to a lariat. When used in this manner, all that is necessary is to hold to the handle and make a slight circular motion whereby the ring 5 forms a true circle and it should be held high enough to clear the floor 15 or ground and, of course, the hands may be changed when the circle is formed and the circle may be brought around the body with great ease. The advantages of this device over an ordinary lariat is that it is made different and 20 will not slip out of shape. It is constructed so as to prevent twisting whereby the original shape may be maintained at all times.

It is to be understood that changes in the details of construction, size, and the like may be 25 resorted to without departing from the spirit and scope of the invention hereinafter claimed.

What is claimed is:—

A toy of the class described comprising a flexible ring, a flexible member attached to one point 30 of the ring, a handle attached to the flexible member and including a rotatable hollow portion to be gripped by the user, and a pair of stops on the ring one on each side of the second-mentioned flexible member.

CARLISLE MARTIN.
